UNITED STATES PATENT OFFICE.

ALBERT S. HOGE, OF WISE, VIRGINIA, ASSIGNOR OF ONE-HALF TO EMORY E. HOGE, OF WASHINGTON, DISTRICT OF COLUMBIA.

TYPE-DISTRIBUTING MACHINE.

SPECIFICATION forming part of Letters Patent No. 540,915, dated June 11, 1895.

Application filed February 7, 1895. Serial No. 537,601. (No model.)

To all whom it may concern:

Be it known that I, ALBERT S. HOGE, a citizen of the United States, residing at Wise, in the county of Wise and State of Virginia, have 5 invented certain new and useful Improvements in Type-Distributing Machines; and I do hereby declare the following to be a full, clear, and exact description of the invention, such as will enable others skilled in the art to 10 which it appertains to make and use the same.

My invention relates to certain improvements in machines for distributing type, and has for its object to provide means for sorting and distributing type taken in blocks or 15 lines from a form or font and depositing each individual type in a separate and distinct receptacle, the type of a given character resting one above the other in lines.

My invention is especially designed to be 20 used in connection with a type setting machine which forms the subject-matter of an application for Letters Patent of the United States filed by me on the 25th day of January, 1895, Serial No. 536,237. The type, when 25 sorted and distributed in their respective receptacles in the present machine, are then fed from said receptacles into the type chutes and hoppers of the type setting machine described in the above noted application.

My said invention consists in certain novelty in the construction, arrangement and combination of the various parts, all of which I will now proceed to point out and describe, reference being had to the accompanying 35 drawings, in which—

Figure 1 is a front elevation of a machine embodying my invention; Fig. 2, a transverse section on line α α of Fig. 1; Fig. 3, a longitudinal section; and Figs. 4 and 5 are details 40 of parts of my said invention.

In this machine each character has a separate receptacle in which it is deposited, but for convenience in illustrating my invention I have only shown in the drawings two of said 45 receptacles and the distributing mechanism connected with each. In practice said receptacles will be arranged in series, side by side, extending from one end of the machine to the other.

Referring to said drawings: the numeral

1 indicates the frame of the machine, on the top of which are secured two horizontal and parallel bars forming tracks or ways, 2.

3 are parallel bars supported upon the bars or ways, 2, and raised above the same so as 55 to leave a space between the said bars and ways.

4 are elongated cam-shaped and parallel slots formed in each bar and raising in steps of a different horizontal plane and raising 60 from one end of the machine to the other. In the drawings I have shown four different planes as at 5, 6, 7 and 8, for the purpose hereinafter described.

9 is a rectangular type distributing box 65 mounted on and adapted to be moved backward and forward on the ways, 2. Said box is of sufficient width to accommodate a type laid lengthwise across said box. The box may be 70 of any desired height and length.

10 are vertical and parallel grooves or guides formed on the inner faces of the sides of the box and at one end of the same.

11 are vertical type holding fingers mounted in the guides and adapted to be moved vertically in said guides. The inner faces of the 75 said fingers are flush with the inner faces of the box and their upper ends are connected by the cross-piece, 12. Said fingers are sufficiently far apart to hold a type laid lengthwise between the same.

13 is a transverse slot in the bottom of the box at right angles to its length and located directly below the guides, 10, and through which the lower ends of the fingers project. 85

14 are inwardly projecting lugs on the lower ends of the fingers, which support the type when placed between said fingers, the ends of the type resting on the lugs.

15 are vertical slots in the sides of the box 90 directly below the guides, and 15^a are vertical slots in the lower part of the type fingers.

16 are outwardly projecting pins on the type fingers which project through the vertical slots, 15, and engage the cam slots, 4, and as 95 the type box is moved back and forward regulate the position of the lower ends of the type carrying fingers with relation to the bottom of the box.

17 are the type receptacles, one being pro-

vided for each character in a font of type. Said receptacles are secured to and extend beneath the ways on which the type box moves and are provided with a removable section, 5 18, which can be detached when filled. The receptacles are made of sufficient size in cross section to receive a single type and are of any desired and convenient length, their upper open ends adapted to communicate with the 10 slot in the bottom of the type box when it is moved over the same. As before stated, only two of these receptacles are shown. In practice they are adapted to be arranged side by side from one end of the machine to the other.

15 18 are plungers mounted in the receptacles provided with a rack, 19, having an escapement movement consisting of a pawl, 20, pivoted to the receptacle and having a rigid member, 21, and a spring member, 22, and a lever 20 arm, 23. The spring member is normally held in engagement with the rack either by gravity or a spring, 24.

25 25 are rods pivoted to the lever arms of the pawls and held in a vertical position by a rod, 26.

30 27 are vertically movable type stops arranged at the top of or receiving end of each receptacle, one on each side of the said receptacles and extending transversely across between the ways on which the type box moves.

35 28 are pivoted key levers having their inner ends pivoted to the stops 27, two key levers carrying a corresponding character being used for each receptacle arranged on opposite sides of the same. The stops have their opposite ends cut away at 29, as shown. When either of the key levers of a given character is operated, the stop is moved up between the lugs of the type fingers, and as the 40 type box is passed over the same said stop engages the type, and as the box continues its movement forces the type off the lugs of the fingers onto the top of the plunger of the receptacle. The lever engaging the rod, 25, 45 operating the escapement device, forces the fixed pawl into engagement and releases the spring pawl. As the lever is released it is returned to its normal position and the rigid pawl is forced down out of engagement with 50 the rack, the spring pawl engaging the same when the weight of the rack or the spring, 24, forces said spring pawl down to the limit of its tension, thus permitting the plunger to be lowered sufficiently to bring the top of the 55 type last deposited on a level with the lugs ready to receive another type.

30 is a spring actuated follower extending transversely across the box and adapted to engage type deposited in the same and force 60 said type toward the discharging slot.

31 is a cut-off located at one side of the discharge slot.

65 The operation of my said invention is as follows: The box is first moved to the extreme left of the ways until the projecting pins of the type fingers engage the highest plane of the cam groove. The upperfaces of the lugs

of the type fingers are then flush with the bottom of the box. The spring follower is then compressed and type taken from a form or 70 font are placed in the box in blocks, so that they will rest in parallel lines, one type above another in each line with the faces toward the front of the machine. The cut-off is then removed and the spring follower forces the 75 first line of type between the type fingers, the ends of lowest type resting on the lugs of said fingers. The cut-off is then replaced between said line and the next adjoining line and the machine is ready for operation. As each line 80 of type is disposed of, the cut-off is removed and the fingers again filled. The operator can then see the character to be first distributed through the slots in the side of the box and type finger. The key for this character 85 on the right of the receptacle, if the box is moving toward the right, is then depressed, which operates one of the stops for this receptacle, moving it up, and as the type box passes over the same the first type engages the stop 90 and is forced off the lugs upon the top of the plunger in the receptacle. The key being released, the plunger lowers and is ready to receive another type on top of the one last deposited. When the box is moving to the left 95 of the machine, the left hand key of the receptacle is used.

As type are of different thickness, I have made the cam slots in steps, each step being in a different plane. For instance, the first 100 plane brings the lugs on a plane with the bottom of the box ready to receive the type. When the fingers are loaded, the box is moved until the pins of the fingers are in the proper plane of the cam slot for a given character to 105 lower said lugs sufficiently below the bottom of the box a sufficient degree to permit the said type to be forced from between the fingers onto the plungers and not be disturbed by the bottom of said box as it passes over. 110 I have arranged the different planes with the lowest which will accommodate the thickest type at the right of the machine, below which plane all the receptacles for the thickest type are arranged; the next plane for the medium 115 type, the next for the thinnest and the last to bring the fingers in position for loading as above described. Of course, as many more planes may be used as may be found necessary. 120

The object of having two keys of the same character is to enable the operator to easily and quickly operate the device, no matter at which end of the machine the box may be. As the bottom type is deposited in its proper 125 receptacle, the next type falls on the lugs of the fingers and the operator can see its face through the slots in the box and fingers. Said box is then moved to the proper receptacle and the operation continued until all the 130 type are distributed.

When the receptacles are filled, their lower portions are removed and placed upon the ends of the chutes of the type setting machine

described in my application hereinbefore referred to and forced by a plunger into said chutes.

Having thus fully described my invention, 5 what I claim as new, and desire to secure by Letters Patent, is—

1. In a machine for distributing type, the combination with suitable ways, a movable type carrying box mounted thereon and provided with a discharge opening or slot in its bottom, vertically movable type holding fingers mounted in said box and passing through the opening, means for automatically raising and lowering the fingers of a series of type 15 receptacles located under the ways, and means for forcing a type from the type fingers into the receptacles, substantially as shown and described.

2. In a machine for distributing type, the combination with suitable ways, a movable type carrying box mounted thereon and provided with a discharge opening in its bottom, vertically movable type holding fingers mounted in the box and passing through the discharge opening or slot, and means for automatically raising and lowering said fingers, of a series of type receptacles located under the ways, and mechanism for forcing the type from the type fingers into the receptacles, and 30 an individual key lever located at each box for operating said mechanism, substantially as shown and described.

3. In a machine for distributing type, the combination with suitable ways, a movable type carrying box mounted on said ways and provided with the discharge slot in its bottom, vertically movable type holding fingers projecting through the discharge slot and provided with inwardly projecting lugs on their lower ends, and outwardly projecting and oppositely disposed pins on their sides, and parallel bars located above the ways and provided with parallel cam slots arranged in a series of different planes, forming steps and 40 adapted to be engaged by the pins on the fingers of a series of type receptacles located below the ways, mechanism for forcing a type from the fingers into the receptacles, and a series of key levers for operating said mechanism, substantially as shown and described.

4. In a machine for distributing type, the combination with suitable ways, a type box, 2, mounted on said ways and having the discharge slot, 13, vertically movable type fingers, 11, mounted in the box and extending through the slot and provided with the lugs, 14, and projecting pins, 16, and the bars located above the ways and provided with cam slots, 4, arranged in a series of different planes 55 and adapted to be engaged by the fingers, of a series of type receptacles arranged under the ways, independent mechanism for fore-

ing the type from the type fingers into the receptacles, and a series of key levers for operating said mechanism, substantially as 65 shown and described.

5. In a machine for distributing type, the combination with a movable type carrying box having a discharge slot, 13, the type holding fingers, 11, mounted in the box and extending through the slot and provided with the lugs, 14, and projecting pins, 16, and the parallel bars having the cam slots, 4, arranged in a series of different planes and adapted to be engaged by the pins, of the series of type 70 receptacles arranged under the ways and provided with the vertically movable type stops, 27, and the key levers, 28, pivoted to said stops, all constructed, arranged and operating substantially as shown and described. 80

6. In a machine for distributing type, the combination with suitable ways, the type box mounted thereon and provided with the discharge slot, 13, and parallel side slots, 15, the type holding fingers, 11, provided with vertical slots, 15^a, lugs, 14, and projecting pins, 16, and the parallel bars having the cam slots, 4, arranged in a series of different planes and adapted to be engaged by the said pins, 16, substantially as shown and described. 85

7. In a machine for distributing type, the combination with a movable type carrying box having the spring actuated plunger, 30, and cut-off, 31, and the discharge slot, 13, of the vertically movable type holding fingers, 11, passing through the discharge slot, and means for operating said fingers, substantially as shown and described. 90

8. In a machine for distributing type, the combination with the type carrying box, 100 mechanism for discharging the type therefrom, one at a time, and suitable key levers for operating said mechanism, a series of type receptacles, each provided with a plunger, and mechanism controlled by the key levers 105 for lowering one of the plungers a given space at each operation of its connected key lever, substantially as shown and described.

9. In a machine for distributing type, the combination with the series of type receptacles, the plungers, 18, mounted in said receptacles and having the rack, 19, of the pivoted pawls, 20, having the rigid members, 21, and spring members, 22, and lever arms, 23, the rods, 25, pivoted to said lever arm, and 110 the key levers, 28, engaging said rods, 25, all constructed, arranged and operating substantially as shown and described.

In testimony whereof I affix my signature in presence of two witnesses.

ALBERT S. HOGE.
